MATERIAL MEASURING AND DISPENSING MACHINE

Robert Lee Goodin, Oakland, Calif.

Application September 4, 1940, Serial No. 355,339

11 Claims. (Cl. 221—105)

The invention relates to machines which are adapted to automatically measure out and dispense predetermined fixed amounts of material taken from a greater mass of the material.

An object of the invention is to provide a machine of the character described which will provide a rapid handling and accurate measuring and dispensing of a wide variety of material made up of solid particles providing a free flowing mass and having particle sizes up to and exceeding approximately three-quarters of an inch.

Another object of the invention is to provide a machine of the character described which will carefully and safely handle various types of material and is especially adapted for use with fragile pieces or particles of food stuff and the like, as for example rice, beans, peas, corn, popcorn, candy, nuts, etc.

A further object of the invention is to provide a machine of the character above which will be adjustable to dispense a wide range of measured quantities varying from a fraction of an ounce up to relatively large mass and volumetric quantities.

Still another object of the invention is to provide a machine of the character described wherein the rate of discharge may be the control for the filling of small containers without danger of clogging the machine.

Yet another object of the invention is to provide a machine of the character set forth which is constructed of a relatively few number of sturdily formed parts which are mounted and arranged to provide positive operation for a substantially indefinitely long period of active use.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawing and description may be adopted within the scope of the invention as set forth in the claims.

Referring to said drawings:

Figure 1 is a vertical sectional view of a machine constructed in accordance with the present invention.

Figure 2 is a plan sectional view of the machine taken substantially on the plane of line 2—2 of Figure 1.

Figure 3 is a cross-sectional view taken substantially on the plane of line 3—3 of Figure 2.

Figure 4 is a cross-sectional view of the ma-

chine taken substantially on the plane of line 4—4 of Figure 2.

Figure 5 is a vertical sectional view taken substantially on the plane of line 5—5 of Figure 2.

Figure 6 is a side elevation of a part of the machine with a portion thereof cut away and shown in section.

With reference to the accompanying drawings, the measuring and dispensing machine therein depicted is assembled on a base or support 6, here fashioned in the form of a rectangular frame by a plurality of angle iron and scrap members. Mounted on the top of the frame is a base plate 7 having integrally formed upstanding longitudinally extending side plates or walls 8 and 9 defining with the plate 7 a longitudinal channel across the top and overhanging the opposite ends 11 and 12 of the frame. Adjacent the right hand end 13 of the plate 7, as viewed in Figures 1, 2 and 6, is a material discharge opening 14 which, as will be seen in Figures 1 and 6, is of elongated rectangular form. Mounted on the side walls 8 and 9 to the left of the opening 14, as viewed in Figures 1 and 6, is a hopper 16 having downwardly converging side walls 17, 18, 19 and 21 which terminate in an elongated rectangular discharge opening 22 at the bottom end of the hopper.

A reciprocative member or carriage 23 is mounted within the elongated channel aforementioned and for longitudinal reciprocation therein and is provided with a receiving chamber 24 which is adapted to move into and out of registration with the hopper opening 22 and the plate discharge opening 14, so as to carry a measured quantity of material away from the hopper and adapted to deliver the same through the discharge opening 14. The carriage, as will be best seen from Figures 1, 3 and 4, consists of a pair of upright side plates 26 and 27 which are held in spaced parallel relation by connecting end members 28 and 29 and are mounted in a trough or depression 31 formed in the base plate 7, so as to guide the longitudinal movement of the carriage. As will be seen in Figure 4, the side plates 26 and 27 of the carriage directly underlie and form a vertical continuation of the longitudinal sides 32 and 33, the sides 32 and 33 depending from the upper tapered hopper sides 18 and 21. Mounted between the carriage side plates 26 and 27 is an elongated inverted channel member 34 having a closed top wall 36 and depending side walls 37 and 38 which are slidably mounted between the carriage walls 26, 27. The channel member 34 is closed at its right hand end, as viewed in Figure 1, by an end wall 39

and bevels downwardly and to the right from the top wall 36 and defines the left hand side of the chamber 24 aforementioned. The opposite longitudinal side of the chamber 24 is defined by a plate 41 which extends transversely across the carriage side plates 26 and 27 and is pivoted on a transversely extending pin 42 carried by these walls. The plate member 41 is normally held in a sloping position, that is inclined downwardly and to the left as viewed in Figure 1, by means of a resilient connection made adjacent the upper end of the member. This connection is here effected by a pin 43 pivoted to the member 41 adjacent the upper end thereof and slidably carried through an opening 44 in the end 29 of the carriage. A helical spring 46 surrounding a part of the pin 43 is normally held in compression between the member 29 and the remote end 47 of the pin, so as to hold the pin with a shoulder 48 thereon engaged against the end member 29 and holding the chamber defining member 41 in inclined position as aforementioned. As the carriage 23 moves to the right, as shown in dotted lines in Figure 1, so as to carry the chamber 24 over the discharge opening 14, the outer end 47 of pin 43 is engaged by a stop member 49 on the end 13 of the base plate 7 to cause the member 41 to rotate in a counterclockwise direction, thereby emptying the contents of the chamber through the opening 14. Preferably, the displacement of the member 41 is sufficient to cause the same to assume a position substantially parallel to the opposite side 39 of the chamber.

As an important feature of the present construction, an improved form of cut-off means is provided for stopping the flow of material into the chamber 24 as the same moves to the right out from under and in registration with the hopper opening 22. As will be seen in Figure 1, this cut-off means consists of a pair of rollers 51 and 52 which are mounted on the hopper and the carriage and which are engaged during the cut-off period so as to seal off the chamber 24 from the hopper opening 52. The roller 51 is here mounted at the chamber side 39 and as will be best seen from Figures 1 and 4, is carried on a central shaft 53 journaled in openings in the side walls 37 and 38 of the carriage member 34. A portion of the member 34 at the juncture of the top 36 and the end wall 39 is cut away so as to expose a portion of the periphery of the roller directly at the top end of the chamber. The roller 52 is carried at the base of the forward end of the hopper opening and as here shown, this end is defined by a slide plate 54 reciprocally carried by the hopper wall 19. Normally the plate 54 is held by gravity and also by means of a spring 56 carried at the upper end of the plate, in a downward position so as to rest the roller 52 upon the top wall 36 of the member 34, the sliding support for the plate, however, permitting the roller a yielding upward movement to permit passage of any particles lodged thereunder. It will thus be seen that as the chamber 24 moves out from under the hopper opening, the roller 51 which is on the following or rearward side of the chamber, will engage the roller 52 on the forward end of the hopper opening so as to cut off the flow of material entering the chamber.

As a further important feature of the cut-off mechanism, the rollers 51 and 52 are rotated to displace their peripheries away from the chamber 24 preceding and during the cut-off period so as to displace particles and pieces of the material engaged between the rollers, away from the rollers

and away from the chamber without injury to the particles. Means for so rotating the rollers is here in the form of a pair of racks 57 and 58 which are mounted on the carriage and on the stationary support respectively and which engage pinions 59 and 61 carried by the roller shafts. As will be best seen from Figures 3 and 4, the rack 58 is carried by the side plate 9 of the stationary support and engages the top of the pinion 61 on roller 51 so as to cause this roller to rotate in a counter-clockwise direction as the carriage moves to the right, as viewed in Figure 1. The rack 57 is carried on arms 62 and 63 secured to the side plate 26 of the carriage and the rack engages the top of pinion 29 on roller 52, so as to cause this roller to rotate in a clockwise direction upon movement of the carriage to the right, as viewed in Figure 1. It will thus be seen that as the rollers approach each other while the carriage is moving to the right, as seen in Figure 1, the rollers will serve to move the material away from the chamber and seal off the top of the chamber at the point of cut-off while positively preventing any material from being caught or crushed between the rollers.

On the return movement of the carriage, that is to the left as viewed in Figure 1, the rollers are rotated in a reverse direction and thus function to assist in the drawing of the material from the hopper into the receiving chamber. This operation of the rollers and the relatively wide expanse of the chamber 24 at the top thereof ensures a rapid filling of the chamber during the period of registration thereof with the hopper opening.

In order to apply a constantly rotating force to the roller 52, regardless of its vertical position within the limits of vertical movement permitted this roller, the rack 57 is supported to permit vertical movement thereof. As will be best seen in Figure 5, the arms 62 and 63 are formed with forked upper ends defining a vertical slot, within which is mounted for vertical movement pins 64 and 66 fixed to the rack 57. Normally, the rack is held in a downwardly pressed position by means of a tension spring 67 which is connected at its upper end to the rack and at its lower end to a pin 68 fixed to the side plate 26 of the carriage, see also Figure 3.

As an important feature of the present construction, the size of the chamber 24 may be readily varied over a relatively wide range so as to enable the machine to dispense various measured quantities of material. In the present construction the chamber size may be changed by adjusting the longitudinal position of the inverted channel member 34 so as to control the position of the chamber defining end 39 of this member. Means for so shifting the member 34 here consists of an elongated screw member 69, see Figure 6, journaled adjacent its forward end 71 in a bracket 72 on the carriage wall 27 and threaded through a member 73 fixed to the wall 38 of the inverted channel member 34 and extending through a longitudinal slot 74 in the carriage wall 27, see also Figure 3. A suitable crank, not shown, may be fastened to the forward end 71 of the screw for rotating the same and longitudinally displacing the inverted channel member to a desired size of the chamber 24. It will be noted that in effecting this adjustment the operation of the roller 51 is left undisturbed by reason of the fact that this roller is mounted on and carried with the chamber 39. In order to hold the chamber in a desired adjusted position, I may lock the screw 69 by means of lock nuts 76

mounted on the screw against the bracket 12. In the smallest position of the chamber, the chamber end 39 is drawn directly to the chamber end plate 41 and the chamber may be reduced to hold as little as a fraction of an ounce of material. On the other hand the chamber end 39 may be moved to the left, as viewed in Figure 1, so as to enlarge the chamber to receive the entire capacity of the relatively large open hopper end. It will be seen that the chamber members 39 and 41, particularly in the larger positions of the chamber, cooperate with the bottom plate 7 to define a chamber. For this reason the end 39 of the member 34 is extended down to and rests upon the plate 7 so as to move any and all material resting on the plate into the discharge opening 14. Preferably, the transverse sides of the end members 39 and 41 are provided with upstanding shoulder or ear portions 11 which bevel into the chamber and effectively wipe the material off from the transverse sides of the chamber, as defined by the carriage sides 26 and 27.

Mounted under the discharge opening 14 is a discharge chute 78 for the material to be dispensed and as will be seen from Figure 1, this chute is provided with a downwardly and outwardly inclined bottom wall 79 which cooperates with opposed side walls 81 to guide material deposited therein to a discharge opening 82 provided in the outer end wall 83 of the chute. Preferably and as here shown, the chute is supported on the end wall 12 of the frame support 6 so as to be entirely independent of the upper member 7 for its support. As an important feature of the present construction, I mount in the bottom wall 79 of the chute a roller 84 which is pivotally supported on an axis at substantially right angles to the direction of flow of the material and has the upper portion of its periphery exposed within the chute. This roller is adapted to be power-operated and rotated to displace the upper periphery thereof in the direction of flow so as to agitate the material being discharged and to urge the same in the direction of the discharge opening 82. Preferably, the roller is non-circular in cross section so as to better agitate and move the material, the form here shown being the one with a series of longitudinally extending circumferentially spaced grooves or corrugations 86. Also preferably, I provide adjacent the discharge end 82 of the chute an adjustable gate 87 which may be set to control the discharge area of the chute so as to limit the rate of discharge of material leaving the chute. This is particularly desirable where material is being filled into relatively small bags having a limited input flow capacity. In such case the gate is adjusted to hold back the material to prevent a choking up of the bag and the chute. When relatively large quantities of material are being dumped into large bags or other containers which can quickly take off the amount of material being dumped, the discharge gate may be moved to its upper position so as to present little or no obstruction to the free discharge of the material. As here shown, the gate 87 may be adjusted by means of a wing nut 88 threaded onto a pin carried by the gate and extending through an elongated slot 89 in the end plate 83. Where material is being filled into relatively small mouthed containers, I prefer to fasten on the discharge end of the hopper a reducer member 91 which as here shown, is formed with an enlarged end which may be telescopically secured on the protruding walls forming discharge opening 82 of the chute.

The drive means for reciprocating the carriage and for rotating the roller 84 in the discharge chute is in the present construction under full manual control so that the rate of movement of the carriage and the rate of discharge may be controlled by the operator. The source of power for driving the several parts is here obtained by an electric motor 92 mounted in the base frame 12. The motor drive shaft 93 is connected by way of suitable reduction gears contained in the gear box 94, and a manually operated clutch, to a crank arm 96. The rotary movement of the latter is converted into a reciprocal movement of the carriage by means of a connecting rod 97 connecting the crank arm 96 to a link 98 which is pivoted at its lower end to the base of the supporting frame and its upper end is pivotally and slidably carried in a lug 99 depending from the end 28 of the carriage. The lug 99 is formed with a downwardly opening vertical slot 101 which receives a pin 102 on the bifurcated upper end 103 of the link 98, the arrangement providing for the aforementioned pivoted and sliding movement and in addition enabling ready dis-association of the link from the lug by lifting off of the top frame members 7. By reason of this latter feature and also by reason of the independent support of the discharge chute from the upper structure of the machine, the top plate 7 and the carriage and the hopper may be readily removed and replaced as a unit. As here shown, the upper plate 7 is detachably held in place at the top of the base frame by means of a plurality of depending pins 104 on the plate 7 which engage through appropriately positioned openings in the top of the frame. In this manner larger and smaller units may be assembled on a single base frame support, thereby giving the machine a very much wider capacity and improved ability to handle various materials.

The opposite end of motor drive shaft 93 is connected by way of suitable reduction gears 106 to the roller 84 in the discharge chute whereby this latter roller is directly driven by the motor. 45 Preferably, an operating shaft 107 for the clutch aforementioned is extended forwardly to adjacent the discharge chute and provided with a lever 108 on its forward end for convenient operation by the operator. Preferably, the lever 108 is arranged as here shown at the same side of the machine as the discharge chute, so that the operator by displacing the lever may cause a movement of the carriage to discharge material as frequently or as often as the operator is able 50 to place a bag or other container in registration with the discharge end of the chute.

I claim:

1. A volumetric measuring machine comprising, a hopper for material to be measured out and having a discharge opening, a reciprocative member mounted for movement across said opening and provided with a receiving chamber of predetermined volume positioned to move in one direction of movement of said member into registration with said opening and in an opposite direction of movement of said member out of registration with said opening, during said last named movement the forward wall of said opening cooperating with the rearward wall of said chamber to cut off the flow of material from said opening into said chamber, and rollers carried by said member and said hopper adjacent said walls and engaged as the chamber is moved out of registration with said opening to cut off the material flow.

2. A volumetric measuring machine comprising, a hopper for material to be measured out and having an open bottom end, a carriage mounted for movement across the open bottom end of said hopper and provided with a chamber for receipt of said material and positioned to move into and out of registration with said hopper end, and material cut-off means comprising a roller mounted on said hopper end, a roller on said carriage adapted to move across the under-side of said first roller and in engagement therewith upon passing of said chamber out of registration with said hopper end, and means rotating said rollers in reverse directions with their adjacent peripheries moving away from said chamber during period of cut-off of said chamber and hopper end.

3. A volumetric measuring machine comprising, a hopper for material to be measured out and having an open bottom end, a carriage mounted for movement across the open bottom end of said hopper provided with a chamber for receipt of said material and positioned to move into and out of registration with said hopper end, and material cut-off means comprising a roller mounted on said hopper end and supported to permit vertical movement thereof, a roller on said carriage at said chamber adapted to move across the under-side of and engage said first roller upon passing of said chamber out of registration with said hopper end, and means rotating said rollers in reverse directions with their adjacent peripheries moving away from said chamber during period of cut-off of said chamber and hopper end.

4. A measuring and dispensing machine of the character described comprising a support, a hopper for material to be measured and dispensed carried by said support and having an open bottom end for gravitation of material therefrom, a member mounted for reciprocal movement under and across the open discharge end of said hopper and provided with a chamber for receipt of said material, said chamber being positioned to move into and out of registration with said hopper end, said hopper end having a wall portion arranged across the line of movement of said member for cutting off the flow of material into said chamber, said wall portion being vertically displaceable, a roller carried at the lower edge of said wall portion and across the line of movement of said member and movable vertically with said wall portion, spring means normally holding said wall portion and roller in a lowered position adjacent the top of said member, a roller carried by said member at substantially right angles to the line of movement thereof and across the rearward edge of said chamber and positioned to engage the under-side of said first roller to cut off the flow of material from said hopper end into said chamber upon movement of said chamber out of registration with said hopper end, and means rotating said rollers adjacent and during period of cut-off of said chamber, said means providing a rotation of said rollers with their adjacent peripheries moving away from said chamber so as to displace material away from the rollers during said period of cut-off.

5. A measuring and dispensing machine of the character described comprising a support, a hopper for material to be measured and dispensed carried by said support and having an open bottom end for gravitation of material therefrom, a member mounted for reciprocal movement un-

der and across the open discharge end of said hopper and provided with a chamber for receipt of said material, said chamber being positioned to move into and out of registration with said hopper end, a roller carried at said hopper end and across the line of movement of said member, a roller carried by said member at substantially right angles to the line of movement thereof and across the rearward edge of said chamber and positioned to engage the under-side of said first roller to cut off the flow of material from said hopper end into said chamber upon movement of said chamber out of registration with said hopper end, and means for rotating said rollers during course of movement of said member and rotating said rollers to displace the adjacent peripheries thereof away from said chamber during period of movement of said member out of registration so as to displace said material away from said chamber during period of cut-off and rotating said rollers in a reverse direction during period of movement into registration so as to draw material into said chamber.

6. A measuring and dispensing machine of the character described comprising a support, a hopper for material to be measured and dispensed carried by said support and having an open bottom end for gravitation of material therefrom, a member mounted for reciprocal movement under and across the open discharge end of said hopper and provided with a chamber for receipt of said material, said chamber being positioned to move into and out of registration with said hopper end, said hopper end having a wall portion arranged across the line of movement of said member for cutting off the flow of material into said chamber, said wall portion being vertically displaceable, a roller carried at the lower edge of said wall portion and across the line of movement of said member and movable vertically with said wall portion, spring means normally holding said wall portion and roller in a lowered position adjacent the top of said member, a roller carried by said member at substantially right angles to the line of movement thereof and across the rearward edge of said chamber and positioned to engage the under-side of said first roller to cut off the flow of material from said hopper end into said chamber upon movement of said chamber out of registration with said hopper end, pinions carried by said rollers, a rack carried by said support and engageable with said member roller pinion, and a rack carried by said member and engageable with said hopper roller pinion, said racks being positioned to rotate said rollers in reverse directions during movement of said member and displacing the adjacent peripheries of said rollers away from said chamber during the cut-off period and rotating said rollers in an opposite direction during movement of said chamber into registration with said hopper end.

7. A measuring and dispensing machine of the character described comprising a support, a hopper for material to be measured and dispensed carried by said support and having an open bottom end for gravitation of material therefrom, a member mounted for reciprocal movement under and across the open discharge end of said hopper and provided with a chamber for receipt of said material, said chamber being positioned to move into and out of registration with said hopper end, said hopper end having a wall portion arranged across the line of movement of said member for cutting off the flow of material into said chamber, said wall portion being verti-

cally displaceable, a roller carried at the lower edge of said wall portion and across the line of movement of said member and movable vertically with said wall portion, spring means normally holding said wall portion and roller in a lowered position adjacent the top of said member and mounted for vertical movement to and from said member, a roller carried by said member at substantially right angles to the line of movement thereof and across the rearward edge of said chamber and positioned to engage the under-side of said first roller to cut off the flow of material from said hopper end into said chamber upon movement of said chamber out of registration with said hopper end, pinions carried by said rollers, a rack carried by said support and engageable with said member roller pinion, and a rack carried by said member and engageable with said hopper roller pinion, said racks being positioned to rotate said rollers in reverse directions during movement of said member and displacing the adjacent peripheries of said rollers away from said chamber during the cut-off period and rotating said rollers in an opposite direction during movement of said chamber into registration with said hopper end, said second named rack being pivoted to permit vertical oscillation thereof to maintain constant engagement with said hopper roller pinion during vertical movement of said hopper roller.

8. A volumetric measuring machine comprising, a hopper for material to be measured out and having a discharge opening, a reciprocative member mounted for movement across said opening and provided with a receiving chamber of predetermined volume to move in one direction of movement of said member into registration with said opening and in an opposite direction of movement of said member out of registration with said opening, during said last named movement the forward wall of said opening cooperating with the rearward wall of said chamber to cut off the flow of material from said opening into said chamber, rollers carried by said member and said hopper adjacent said walls and engaged as the chamber is moved out of registration with said opening to cut off the material flow, and means for adjusting the spacing between said chamber wall and an opposite chamber wall to regulate and control the volume of said chamber.

9. A material measuring and dispensing machine comprising, a hopper for material having an elongated substantially rectangular discharge opening in the bottom thereof, an elongated carriage mounted for movement under said discharge opening and having a base and a pair of vertical side walls substantially engaged with and forming a vertical continuation of the elongated sides of said opening, an inverted channel shaped member including a top and depending sides mounted between said walls and having a closed end sloping from adjacent said top to said base, a member mounted across said carriage side walls and longitudinally spaced from said member end to define therebetween and with said base a receiving chamber adapted to be moved upon reciprocation of said carriage into and out of registration with said

opening, a roller carried by said first member at the top of said closed end and arranged across the line of movement of said carriage, a roller carried by an end wall of said opening across the line of movement of said carriage and engaged by said first roller upon movement of said chamber out of registration with said opening, and means for rotating said rollers during movement of said carriage to displace the adjacent peripheries of said rollers away from said chamber during movement of the latter out of registration and to displace said roller peripheries towards said chamber upon movement of said chamber into registration.

10. A material measuring and dispensing machine comprising, a hopper for material having an elongated substantially rectangular discharge opening in the bottom thereof, an elongated carriage mounted for movement under said discharge opening and having a base and a pair of vertical side walls substantially engaged with and forming a vertical continuation of the elongated sides of said opening, an inverted channel shaped member including a top and depending sides mounted between said walls and having a closed end sloping from adjacent said top to said base, a member mounted across said carriage side walls and longitudinally spaced from said member end to define therebetween and with said base a receiving chamber adapted to be moved upon reciprocation of said carriage into and out of registration with said opening, a roller carried by said first member at the top of said closed end and arranged across the line of movement of said carriage, a roller carried by an end wall of said opening across the line of movement of said carriage and engaged by said first roller upon movement of said chamber out of registration with said opening, means for rotating said rollers during movement of said carriage to displace the adjacent peripheries of said rollers away from said chamber during movement of the latter out of registration and to displace said roller peripheries towards said chamber upon movement of said chamber into registration, and means for displacing said inverted channel member relative to said carriage to change the size of said chamber.

11. A material measuring and dispensing machine comprising, a support including an elongated plate having a discharge opening and a hopper mounted above said plate and having an open discharge end spaced longitudinally from said opening, an elongated longitudinally reciprocative member mounted on said plate under said hopper end and provided with longitudinally spaced transversely extending upwardly divergent walls defining a receiving chamber, means for displacing said member to move said chamber from a position in registration with said hopper end to a position over said opening, the leading wall of said chamber during said movement being pivoted for rotation about a horizontal transverse axis to discharge the contents of said chamber through said opening, and means automatically rotating said last named wall upon movement of said chamber over said opening.

ROBERT LEE GOODIN.
